UNITED STATES PATENT OFFICE.

GEORGE WALE, OF TROY, NEW YORK, ASSIGNOR OF ONE-HALF TO FRANK P. IRVING, OF SAME PLACE.

DESIGN FOR A KALEIDOSCOPE-STANDARD.

SPECIFICATION forming part of Design No. 30,309, dated March 7, 1899.

Application filed January 30, 1899. Serial No. 703,902. Term of patent 14 years.

To all whom it may concern:

Be it known that I, GEORGE WALE, a citizen of the United States, residing at the city of Troy, county of Rensselaer, State of New

5 York, have invented and produced a new and original Design for Kaleidoscope-Standards, of which the following is a specification, reference being had to the accompanying drawings, wherein—

10 Figure 1 is a view in side elevation of a kaleidoscope-standard embodying my new design. Fig. 2 is a top plan view of the same; and Fig. 3 is a horizontal section of the same, taken on the broken line 3 3 in Fig. 1, showing the lower horizontal part in plan.

15 The design consists in the ornamental shape of the standard.

The lower part 2 of the standard has a circular horizontal top 1, as shown in Figs. 2 and 3.

20 The upright part of the standard 3 is V-shaped or angular in cross-section, and is above and in vertical alinement with a sector

of the circular top 1, and has its outer side open, as seen at 7. This upright part 3 tapers gradually toward its upper end, which has an enlargement 6.

25 The intermediate part 5 of the standard extends in arched form from the lower end of the upright part to the lower part 2.

30 The leading feature of the design consists in the angular upright part above and in vertical alinement with a sector of the circular lower horizontal part and having its outer side open.

35 What I claim as new, and desire to secure by Letters Patent, is—

The design for a kaleidoscope-standard herein shown and described.

40 In testimony whereof I have hereunto set my hand this 28th day of January, 1899.

GEORGE WALE.
